PORTRABLE FIREPLACE HEATER

Filed Oct. 8, 1937

UNITED STATES PATENT OFFICE

2,183,458

PORTABLE FIREPLACE HEATER

Richard A. Lathrop, Hope, N. Dak.

Application October 8, 1937, Serial No. 168,062

3 Claims. (Cl. 126—121)

This invention consists of a portable fireplace heater an object of which is to provide a compact unit, made of metal or other suitable material, which may be installed in an open fireplace or in any other part of a room in the same manner as a heating stove.

Among the objects accomplished by the present invention is the provision of fresh air circulation, without use of mechanical power, by induction of the outside air through the combustion zone of the heater and ejecting the heated fresh air into the room in a manner to resist incoming cold air through the doors and windows; the provision of a dead air space between the heater and wall or partition of the room or house; the provision of a heater capable of burning any kind of fuel; the provision of a heating unit susceptible of enlargement or diminution as well as the extension of the heating area to an additional room or rooms; and the provision of a knockdown fireplace or heater which may be quickly assembled and disassembled and conveniently transported.

Other objects of the invention will be apparent from the following description of the present preferred form of the invention, taken in connection with the accompanying drawing, wherein:

Fig. 1 is a front elevational view, partly in section, of a heater constructed in accordance with the present invention illustrating its application, and

Fig. 2 is a vertical sectional view of the same.

In the drawing in order to illustrate the application of my invention, a portion of a building is illustrated including a floor 3, wall 4 and ceiling or roof 5. The heater of the present invention consists of a unit, generally designated 6, preferably made of metal and of any desired shape or size. In illustrating the application of my invention, the unit is shown to be of rectangular configuration embodying a base or bottom wall 7 with upstanding ends 8, rear wall 9 and front wall 10. The top of the unit is closed, as indicated at 11, except for an opening in which a stack 12 is mounted, the latter being used for carrying off the products of combustion in a manner more fully hereinafter set forth. Preferably the base 7 of the unit is spaced from the floor 3 by brick, tile or the like 13, so as to insulate the bottom of the unit from the floor.

The bottom of the unit comprises a fuel compartment 14 which may be equipped with oil, gas, electricity or like fuel medium, or if desired, wood or coal may be used. Immediately above the fuel chamber is a combustion zone 15 through

which the products of combustion pass before exhausting into the stack 12.

It is of the essence of importance in the present invention to induce outside air into a conduit forming a part of the unit, the conduit extending upwardly through the fuel chamber and combustion zone in order that the outside heated air may be projected into the room to be heated. To accomplish this result, I provide an air inlet pipe 16 which in the present instance is shown to extend below the floor 3 and leads to the outside, the atmosphere being carried therethrough into an air jacket 17 which forms the back of the fuel compartment 14, the air jacket extending over the top of the fuel compartment and terminating just short of the front wall 10 of the unit. The air jacket is in communication with a plurality of superposed communicating air chambers 18 which preferably extend the full length of the unit and alternately extend forwardly and rearwardly in the unit in contiguity with the adjacent walls of the latter whereby the products of combustion are compelled to travel in a tortuous path around the air chamber preparatory to entering the stack 12. The air chambers 18 are interchangeable and may be increased or diminished at the option of the user, the number of chambers used being usually dependent upon the space available for the unit and the size of the room or rooms to be heated.

Upon reference to Fig. 2 of the drawing it will be noted that the air jacket 17 is spaced from the wall 4 and since the jacket extends over the complete inner or rear wall of the fuel compartment, the wall is protected from the heat. Immediately above the air jacket 17 is a dead air space 19 which is provided so as to separate the stack 12 from the wall 4 between the combustion zone of the unit and the roof or ceiling 5. The air in the dead air space 19 may be exhausted through suitable openings 20.

In addition to the induction of outside air through the unit, I also make provision for the inlet of inside air through openings 21 formed in the opposite end walls of the unit adjacent the base 7. The inside air passes upwardly through the fuel compartment 14, combustion zone 15 and into the stack 12. In addition the front wall of the unit is provided with an opening through which the fuel compartment is accessible. This opening may be covered in whole or in part by any suitable type of closure, one form of closure being indicated in the drawing at 22. Thus provision is made for an open front

fireplace or a closed front heater of fireplace design.

5 In the top of the unit just above the upper air chamber I provide a humidifying compartment 23 which may be equipped with a water pan 24 or the like to augment the room humidity while the unit is in operation.

10 If desired the combustion gases from zone 15 may be by-passed from in back of the heater proper into another room parallel to the room in which the unit is mounted in the same manner as the smoke pipe 25 extends from the stack 12. When this is done the stack 12 is placed on the opposite side of the wall 4, to provide additional heat for said parallel room. Also, if desired, the stack 12 may be continued upwardly, as indicated at 26, into an upstairs room, preparatory to exhausting through a chimney in the roof of the building.

15 20 The fresh heated air travelling upwardly through the pipe 16, jacket 17 and air chambers 18, is ejected into the room through outlets 27 formed in the closed top 11 of the unit. To augment passage of the ejected fresh air to parts 25 of the room remote from the unit, at the same time preventing the ejected air from entering the foul air openings 21, a differential in the size of said latter openings and the pipe 16 is effected. Preferably this is accomplished by making the 30 combined areas of the openings 21 less than the opening in the pipe 16, the variance in size being approximately ten to fifteen degrees. This also tends to repulse incoming cold air through doors and windows of the room.

35 It is, of course, understood that the device of my invention is not only portable, but may be varied in size to be accommodated in any desired space. However, the principle of operation under all conditions remains the same since the unit 40 will not contact the floor or walls of the room in which it is mounted not only providing an inside air circulating space around the unit, but likewise protecting the wall and floor from the heat of the unit. In addition the outside air is 45 carried directly through the fire zone and then ejected into the room while the inside air finds

its way into the fuel chamber where it mingles with the combustion gases and is carried upwardly through the stack.

5 While I have herein described a preferred form of my invention, it is nevertheless to be understood that various changes may be made therein, especially in the details of construction, proportion and arrangement of parts within the scope of the claims hereto appended.

10 What is claimed is:

1. A portable fireplace heater including a heating unit embodying a fuel chamber and combustion zone with a stack issuing from the latter, an outside air conduit extending into the fuel chamber and completely covering the rear wall of the 15 latter, said conduit extending through the unit combustion chamber and exhausting at a point above the latter, and inside air conduits arranged on the sides of the fuel chamber and opening into the combustion chamber and stack, the combined 20 areas of the inside air conduits being less than the area of the outside air conduit to augment passage of ejected fresh air and minimize possibility of air passage into said inside air conduits.

2. A portable fireplace heater including an in- 25 closed heating body, an air conduit leading from a point remote from said body into the latter and opening through the top wall of the body, said body being provided with foul air inlet openings adjacent its base leading into the combus- 30 tion zone of the heating body, the combined area of said foul air openings being less than the area of the opening in the air conduit.

3. A fireplace heater including an enclosed 35 heating body, an air conduit leading from a point remote from said heating body and extending through the latter in the path of the heating gases of said body, the conduit being closed throughout and opening through the top of the heating body, said body being provided with foul 40 air inlet openings, adjacent its base, leading into the combustion zone of the heating body, the combined area of said openings being less than the area of the air conduit opening.

45 RICHARD A. LATHROP.
